UNITED STATES PATENT OFFICE.

EDWARD H. HEBERN, OF OAKLAND, CALIFORNIA, ASSIGNOR TO H & H PATENT DEVELOPING COMPANY, OF OAKLAND, CALIFORNIA.

ELECTRIC TYPEWRITING MACHINE.

Application filed September 8, 1919. Serial No. 322,568.

To all whom it may concern:

Be it known that I, EDWARD H. HEBERN, a citizen of the United States, residing at Oakland, in the county of Alameda and State of California, have invented new and useful Improvements in Electric Typewriting Machines, of which the following is a specification.

The object of the present invention is to provide an improved electric typewriting machine, such that a small depression of the typewriter keys will be sufficient to actuate the type for printing, and by which the printing can be effected more easily and quickly than heretofore, and with absolute uniformity of pressure, notwithstanding variations in the pressure applied to the keys by the operator.

In the accompanying drawing, Figure 1 is a transverse vertical section of my improved electric typewriting machine, certain parts not material to the invention being omitted; Figure 2 is a front view of a detail; Figure 3 is a sectional view of a detail of construction; Figure 4 is a broken view similar to Figure 1, but with the parts shown in a different position from that shown in Figure 1; Figure 5 is a sectional view of a disc; Fig. 6 is a view in elevation of the disk shown in Fig. 5; Figure 7 is a broken transverse vertical section showing a modification of the invention; Figure 8 is a similar view, but looking from the opposite side, of parts employed in such modification.

Referring to the drawing, 1 indicates a frame or casting supporting most of the apparatus for converting any ordinary typewriter machine to my improved electric typewriting machine and supporting the ordinary typewriter upon bosses 2, screws passed through said bosses being screwed into the frame of said typewriting machine to secure it to said frame 1; 4 indicates the keys of the typewriting machine connected to key bars 6 pivoted at 7, and to said key bars 6 are pivotally attached, as shown at 8, hangers 9, the lower ends of which carry pins 11 movable in vertically extending slots 12 in the front ends of key levers 13 pivoted at 14. To each hanger is pivoted, as shown at 16, the central portion of a flat spring 17, which central portion lies closely adjacent to the hanger 9 while the terminal portions are bent outwardly therefrom and engage

the ends of the pins 8 and 11 respectively on opposite sides of a key bar 6 and lever 13 respectively. The lower end of said hanger is enlarged or extended forwardly, as shown at 18, to engage and lift up the reduced end of a contact carrier 19 of fiber or other insulating material, pivoted to a bar 21 extending longitudinally of the machine and carrying a contact 22 pressed down by a spring 23. The slightest pressure on the typewriter key removes the extension 18 from engagement with said contact carrier 19, whereupon the contact carrier 19 and the contact 22 drop and the latter comes into contact with a contact 24 screwed into a longitudinally extending metal frame 26, attached to casting 1 by a screw 27 (Fig. 3) insulated from said casting by washers 28 and an insulating ring 29.

To said frame piece 26 is electrically connected by a screw 31 to a terminal 32 connected a wire 33 electrically connected to a rheostat 34, the two poles of the rheostat being connected to wires 36 connected to opposite sides of a battery 37. The rotary member of the rheostat 34 is electrically connected to a wire 38, which is electrically connected to a metal block 39 secured by means of screws 41 to an insulating block 42, secured by screws 43 to the frame 44 of the typewriting machine.

Said metal block carries an adjustable contact 46 which is normally in contact with a contact 47 carried by an arm 48 extending from a rotary disc 49, said arm 48 being drawn downwards, so as to make contact between the contacts 46 and 47, by a coiled spring 51 secured to said arm 48 and to an arm 52 pivoted upon said block, as shown at 53, and having an arcuate slot 54 through which passes a set screw 56 to regulate the strength of said spring 51. Connected to said arm 48 is a wire 57 electrically connected to a terminal 58, which terminal is supported by a screw 59 upon a fiber rod 61 embedded in wax 62 cast around solenoids 63. From said terminal 58 extend wires 64 of said solenoids, the other ends of the wires of said solenoids extending, as shown at 66, to individual terminals 67 supported upon a longitudinally extending insulating bar 68. From said terminals 67 there extend wires 69 to contacts 71, extending through a longitudinally extending insulating bar 72 arranged in the frame or casting 1 in 110

front of the contact carriers 19, a spring contact 23 extending from each contact 71 and contacting with a plate 74 in contact with the contact 22.

5 With this construction, when an operator presses a key through the distance between the contacts 22 and 24, and closes the circuit between the said contacts, the corresponding solenoid is energized, thereby drawing upwards the core 76 of said solenoid and the rear end of the key lever 13, the front end then descending and completing the depression of the key bar 6 and actuating the type bar 77 by means of a link 78 pivotally connected to said key and type bars. Before, however, the core 76 strikes a rubber stop 78, a protuberance 79 on the type bar strikes against an end of a shifter 81, the other end of which impinges against a roller 82 on a lever 83 and draws said lever 83 out of engagement with an escapement wheel 84, allowing the escapement to operate the carriage carrying the typewriter platen 86, so that the platen moves slightly; at the same time, the roller 82 operates an arm 87 secured to the disc 49 and breaks a circuit between the contacts 46 and 47. Although the circuit is broken through the solenoid, the core still moves upwards, due to its momentum, and the type bar moves onward towards the typewriter roller 86, until the core is arrested by striking the lower end of the rubber stop 78 secured to a metal stop 88 screwed into the upper portion of the casing 89 for the solenoids and locked therein by a lock-nut 90. Even after the core is arrested by striking the rubber stop 71, the type moves forward to the roller 86 due to the flexibility of the type bar and makes an imprint upon the roller. Then, by reason of its elasticity the type bar immediately rebounds from the roller and is drawn back to its original position against a flexible cushion 91, due to the ordinary spring 91' for retracting the type bar. These springs can be made very much stronger than with an ordinary typewriter so that type bars can be made to come back very much more quickly than the type bars of an ordinary typewriter, thus increasing the range of speed of the operator. The power for overcoming said springs, being not now dependent upon the exertion of the operator, but being derived from the electric circuit, can be greatly increased without in the slightest degree increasing the work of the operator.

10 The falling back of the type bar 77 to its normal position of rest upon the rubber cushion 91 raises the key lever 13 and thereby raises the contact carrier 19, breaking the circuit between the contacts 22 and 24. But in order that the circuit between the contacts 46 and 47 may not be closed again before the circuit between the contacts 22 and 24 is opened, I provide an arm 92 secured to

15 the disc 49 and carrying an adjustable weight 93. The purpose of this arm is to increase the swing of the disc 49, taking place in the time elapsing between the opening between the contacts 46 and 47, and the opening between the contacts 22 and 24 and resisted by the coiled spring 51. But for this arm and weight, the spring 51 would actuate the arm 48 to close the contacts 46, 47, before the type bar has resumed its normal position, that is, before the contacts 22, 24 were opened, which would again energize the solenoid and cause an indefinite succession of impacts of the type bar against the typewriter roller. By supplying the weight 80 ed arm 92 to the disc 49, the distance through which the disc swings is rendered so great as to cause the circuit between the contacts 46, 47 to close after the circuit between the contacts 22, 24, has been opened. 85 94 indicates a spacing bar connected to an end of a spacing lever 96, the other end of which is connected to an end of a rod 97, the other end of which is connected to an end of a lever 98, pivoted at 99, the other end 90 of said lever being connected to an end of a link 101, the other end 102 of which is forked and engages a knob 103 on the lower end of the escapement lever 83, whereby said escapement is actuated by the depression of 95 said spacing bar. The spacing bar is also connected to a hanger, which is supplied with contacts 22, 24, a lever 19, and solenoid 63, the same as the keys 4.

100 The shift key 104 is likewise supplied with a hanger, contacts 22, 24, lever 19 and a solenoid 63, but the shift key, not being connected to any type bar, does not in operation swing the disc 49 and open the circuit between the contacts 46, 47, but the circuit between these contacts remains closed until it is opened by the operation of a letter key.

105 When it is desired to turn the platen, instead of shifting it longitudinally, the rack 106 is withdrawn from the escapement wheel 110 84 by means of an arm 108 (Fig. 8), having an upwardly extending finger 109 adapted to be moved by the operator into engagement with a spring-actuated dog 111, to hold it in the upper position, the upward movement of the arm being limited by a stud 112, extending through a hole 113 in said arm. Said arm is attached at its lower end to a slide piece 114, in which said rack 106 slides. The arm 108 is normally drawn into the position in which said rack 106 engages said escapement wheel 84 by coiled springs 116. The rack 106 being drawn out of engagement with the escapement wheel 84, the platen is given a rotary motion by means of a pawl 117, pressed by a spring 118 against a stop 119 and carried by a lever 121 attached to a link 122, secured at its lower end to a longitudinally extending bar 123 resting upon arms 124, pivoted upon the shaft 14 and 120 125 126 127 128 129 130

drawn downwardly by springs 126, said bar 123 extending over the levers 13, so that, when any one of the levers 13 is rocked upwards about its pivot 14, the bar 123 is 5 raised, thereby withdrawing the pawl from a ratchet wheel 127 attached to the platen, so that a downward movement of the bar actuates the pawl to advance the platen through any desired angle. When it is 10 not desired to use the means for advancing the platen circumferentially, the bar is held in a continually raised position by turning the arm 124 on the shaft 14 and holding them by set screws 128.

15 I claim:—

1. In an electric typewriting machine, the combination of a pivoted key bar, a contact moved thereby, a second contact, from contact with which the first-named contact is 20 normally held by said key bar, an electro-magnetic device energized by the closing of a circuit through said contacts, a type bar moved toward the platen of the typewriting machine by the energization of said electro- 25 magnetic device, and a normally closed second pair of contacts in said electric circuit and opened by the movement of said type bar toward the platen of the typewriting machine.

2. In an electric typewriting machine, the combination of a pivoted key bar, a contact moved thereby, a second contact, from contact with which the first-named contact is 30 normally held by said key bar, an electro- 35 magnetic device energized by the closing of a circuit through said contacts, a type bar moved toward the platen of the typewriting machine of said electro-magnetic device, a normally closed second pair of contacts 40 in said electric circuit and opened by the movement of said type bar toward the platen of the typewriting machine, and a weighted device movable with the movable contact of said second pair.

3. In an electric typewriting machine, the combination of a pivoted key bar, a contact moved thereby, a second contact, from contact with which the first-named contact is 45 normally held by said type bar, an electro- 50 magnetic device energized by the closing of a circuit through said contacts, a lever moved by the energization of said electro- 55 magnetic device, the movement of said lever depressing said key bar, a type bar actuated by the depression of said key bar, and a normally closed second pair of contacts in said 60 electric circuit and opened by the movement of said type bar toward the platen of the typewriting machine.

4. In an electric typewriting machine, the combination of a pivoted key bar, a contact moved thereby, a second contact, from con-

tact with which the first-named contact is normally held by said key bar, an electro-magnetic device energized by the closing of 65 a circuit through said contacts, a lever moved by the energization of said electro-magnetic device, the movement of said lever depressing said key bar, a type bar actuated by the depression of said key bar, a normally closed second pair of contacts in said 70 electric circuit and opened by the movement of said type bar toward the platen of the typewriting machine, and a weighted device movable with a movable contact of said 75 second pair.

5. In an electric typewriting machine, the combination of a pivoted key bar, a hanger attached thereto, a pivoted contact carrier, a contact carried thereby, a second contact, from contact with which the first-named contact is normally held by said hanger, an electro-magnetic device energized by the closing of a circuit through said contacts, a lever moved by the energization of said 80 electro-magnetic device, the movement of said lever depressing said key bar, a type bar actuated by the depression of said key bar, and a normally closed second pair of contacts in said electric circuit and opened 85 by the movement of said type bar toward the platen of the typewriting machine.

6. In an electric typewriting machine, the combination of a pivoted key bar, a hanger attached thereto, a pivoted contact carrier, a contact carried thereby, a second contact, from contact with which the first-named contact is normally held by said hanger, an electro-magnetic device energized by the closing of a circuit through said contacts, a lever moved by the energization of said 90 electro-magnetic device, the movement of said lever depressing said key bar, a type bar actuated by the depression of said key bar, and a normally closed second pair of contacts in said electric circuit and opened 95 by the movement of said type bar towards the platen of the typewriting machine.

7. In an electric typewriting machine, 100 the combination of a pivoted key bar, a contact moved therewith, a second contact from contact with which the first-named contact is normally held by said key bar, an electro- 105 magnetic device energized by the closing of said contacts by movement of the key bar, a type bar moved toward the platen of the typewriting machine by the energization of said electro-magnetic device, said electric circuit being opened by the movement of 110 said type bar toward the platen of the typewriting machine.

EDWARD H. HEBERN.
